COMBINED COMPACT AND MAKEUP MIRROR

Ted I. Kingsford, Memphis, Tenn., assignor to
Plough, Inc., Memphis, Tenn.

Original design application Jan. 14, 1974, Ser. No.
433,434, now Patent No. 238,310. Divided and
this application Sept. 22, 1975, Ser. No. 615,327

Term of patent 14 years

Int. Cl. D3—01
U.S. Cl. D86—10 N

FIG. 1

FIG. 5

FIG. 2

FIG. 3

FIG. 4

FIG. 1 is a front perspective view of a combined compact and makeup mirror showing my new design in open condition;

FIG. 2 is a top plan view in closed condition;

FIG. 3 is a rear perspective view of FIG. 1;

FIG. 4 is a front elevational view of FIG. 2; and,

FIG. 5 is a rear elevational view of FIG. 2.

This is a division of application Ser. No. 433,434 filed on Jan. 14, 1974, now design Pat. No. 238,310.

I claim:

The ornamental design for a combined compact and makeup mirror, substantially as shown and described.
